UNITED STATES PATENT OFFICE

2,433,110

SINGLE HAND OPERATED CARD PUNCH

Hyman Gardner, Brooklyn, N. Y.

Application December 22, 1945, Serial No. 636,902

2 Claims. (Cl. 164—86)

1

This invention relates to a card-punching device which is removably attachable to a table or other support.

An object of this invention is to provide an easily manipulated card punching device which is particularly adapted for use in restaurants for punching holes in customers' checks to indicate the amount owed by the customer.

Another object of this invention is to provide a card punching device having means for operating the punching tool by using one hand only, and having means for automatically returning the operating mechanism to its initial position after use.

Another object of this invention is to pivotally mount the punching tool carrying casing and to position the casing at a favorable angle, so that a card to be punched may be readily placed in the device by the fingers of one hand of the user and the device operated by the same hand for punching and with a single downward motion.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation of the card punching device, partly broken away to show the interior operating mechanism.

Figure 2 is a top plan view of the device.

In the illustrated embodiment of the invention, the numeral 10 indicates a card punching device, comprising a support 11 having a C-shaped bracket 12 for detachably securing the punching device 10 to a table or counter.

The C-shaped bracket 12 has a thumb screw 13 threaded therein. At the upper end of the thumb screw 13 is a collar 14 which comes into engagement with the counter.

The support 11 has a hollow upper end 15 and an end wall 16 in which is threaded a screw 17. A locknut 18 threaded on the screw 17 serves for locking the screw. The inner end of the screw 17 is formed to provide an obtuse angular cavity or substantially V-shaped fulcrum 19.

An elongated hollow casing 20 is pivotally mounted on a pin 21 fixed transversely of the support 11. The casing 20 may thus be moved up and down to and from the support 11.

The support 11 has a central opening 22 which

2

terminates at its upper end at the side 23 and at its lower end at the side 24.

The up and down movements of the casing 20 are limited by the sides 23 and 24.

5 A punching tool 25 is slidably mounted in a carrier 26 which is suitably fastened in the interior of the casing 20 by a screw 27. The carrier 26 has a slot 28 extending therethrough in a crosswise direction. The slot 28 is positioned 10 in the path of the punching tool 25 and is adapted for receiving a card 30 to be punched. The lower surface 31 of the slot 28 extends some distance below the punching tool.

As shown in Figure 1, a coil spring 32 is 15 mounted on the punching tool 25 and positioned between an end of the carrier 26 and a pin 33 which passes transversely of the punching tool 25.

A link-like connecting member 34 has one of 20 its ends pivotally connected with the pin 33. The other end 35 of the link-like member 34 is knife-shaped and in the form of an acute angle. This angular end portion of the member 34 seats in the fulcrum 19.

It is to be noted that in the arrangement shown, 25 the spring 32 automatically retains the operating mechanism 36 in a raised position so that the upper surface 37 of the casing 20 is in contact with the side wall 23 of the support 11.

In the position shown in Figure 1, the operating mechanism 36 is positioned at a favorable angle, so that a card 30 to be punched may be 30 readily placed in the device by the fingers of one hand of the user and the device operated for punching the card with a single downward motion.

35 It will be readily seen that when the operating mechanism 36 is lowered, that its downward motion is limited by the lower side 24 of the support 11. The arrangement shown makes it possible to actuate the operating mechanism 36 with a very light downward pressure.

It is to be noted that the nut 18 may be unthreaded to permit the screw 17 to be adjusted 40 so as to bring the cutting end of the punching tool 25 in position to clear the slot 28 and be ready for immediate punching operation.

As best shown in Figure 1, the lower face portion 38 of the hollow casing 20 has a rib 39 integral with the casing and extending between 45 two vertical side walls of the casing. A plate 40 is pivotally mounted at the lower face 38 on a screw 41 which is threaded in the rib 39.

The plate 40 covers the entire distance between the rib 39 and the outer face 42 of the 50 casing. The plate 40 forms a closure so that

the lower portion of the casing 20 provides a collecting chamber 43 in which chips from the punched cards collect. When the chamber 43 is filled with chips, the user swings the plate 40 sideways so as to empty the contents of the chamber 43.

The support 45 has a hollow upper end 47 in which a pin 48 is fixed in a horizontal plane. A hollow casing 49 is pivotally mounted on the pin 48.

A punching tool 50 is slidably mounted in the casing 49. The free end of the tool 50 has a roller 51 rotatably mounted thereon on a pivot 52. A coil spring 53 is mounted on the punching tool 50 and reacts against a collar 54 integral with the tool 50 and provides pressure whereby the roller 51 forcibly contacts an abutment 55 at the central portion of the support 46.

It is to be noted that the upper portion of the abutment 55 is angularly directed so as to cause the casing 49 to be automatically retained in a raised position as limited by a sidewall 56 at the upper elevation of the support 46.

When the operating mechanism 57 is lowered, its downward motion is limited by the lower side 58 of the support 46.

In accordance with the patent statutes I have described and illustrated the preferred embodiment of my invention, but it will be understood that various changes and modifications can be made therein without departing from the spirit of the invention as defined by the appended claims.

I claim:

1. A card punch having in combination, a support having means for detachably securing to a table, a hollow casing pivotally mounted for up and down movement on said support, and having a chip collecting chamber, a punching tool reciprocally mounted in said casing, said casing being formed with a slot in the path of said punching tool for receiving a card to be punched, said card being received in cutting position at the lower surface defining said slot during the entire movement of said casing and said plunger into operating position, said casing having a link-like connecting member for moving said punching tool, one end of said connecting member being pivotally connected to said punching tool, a substantially V-shaped fulcrum in said casing below

said pivot, the other end of said connecting member being knife-shaped and seating in said fulcrum, said punching tool being thereby actuated when said casing is moved downwardly to said support, and a spring moving said punching tool into retracted position and said casing upwardly into inoperative position.

2. In a single-hand operated card punch, in combination, a support having means for detachably securing to a table, a hollow casing pivotally mounted on said support and having a chip collecting chamber, a punching tool reciprocally mounted in said casing, said casing being formed with a slot in the path of said punching tool for receiving a card to be punched, said card being received in punching position at the lower surface defining said slot prior to and during the entire movement of said casing and said plunger into operating position, said casing having a link-like connecting member for moving said punching tool past said slot when said casing is moved downwardly to said support, one end of said connecting member being pivotally connected to said punching tool, a substantially V-shaped fulcrum in said casing below said pivot, the other end of said connecting member being knife-shaped and seating in said fulcrum, said punching tool and said connecting member being pivotally mounted in obtuse angular relation with each other, a coil spring mounted on said punching tool causing said punching tool to move into retracted position and said casing to move upwardly into inoperative position, said fulcrum being threadably mounted in said casing to cause a regulated pressure on said spring.

HYMAN GARDNER.
